UNITED STATES PATENT OFFICE.

JOSEPH JOHNSON, OF LEBANON, PENNSYLVANIA.

CHAIN-MAKING APPARATUS.

Application filed October 29, 1921. Serial No. 511,438.

To all whom it may concern:

Be it known that I, JOSEPH JOHNSON, a citizen of the United States, residing at Lebanon, in the county of Lebanon and State of Pennsylvania, have invented certain new and useful Improvements in Chain-Making Apparatus, of which the following is a specification.

One object of my invention is to provide improved apparatus for inserting studs in chain links such for example as in heavy chains where it is desired to reinforce and strengthen the links.

Another object is to facilitate and expedite the insertion of said studs and at the same time insure that the studs are properly secured in place.

These objects, and other advantageous ends which will be described hereinafter, I attain in the following manner, reference being had to the accompanying drawings in which

Figure 1 is an end elevation of apparatus made in accordance with my invention.

Figure 2 is a sectional plan view showing a link in position ready to receive a stud; the section being taken on the line 2-2 of Figure 1.

Figure 3 is a view of the same general character as shown in Figure 2; the parts having been operated to secure the stud in place.

Figure 4 is a section taken on the line 4-4 of Figure 2, and

Figure 5 is a section taken on the line 5-5 of Figure 3.

Referring to the drawings, 6 represents a base or supporting structure which is preferably made exceptionally heavy and can be made out of one or more blocks of metal. The base has two upwardly extending parallel portions 7 which are spaced apart to provide a slideway for a plate 8; said plate resting on the top surface 9 of the base 6. The plate 8 adjacent one end has a transversely extending block 10 secured thereto adapted to serve as an abutment member for a die block 11 which is mounted on the top of the plate with its

opposite ends in slidable engagement with the portions 7. A second die block 12 has its opposite ends preferably secured to the rear parts of the portions 7 and the opposed upright surfaces 13 and 14 of the die blocks

11 and 12 are concaved as clearly shown in Figures 2 and 3.

A stud supporting pedestal 15 is secured to the top of the base 6 and projects upward through a hole 16 in the plate 8. The upper surface of the pedestal 15 is grooved as shown at 17; the groove extending from the front to the rear end of the pedestal and being preferably of a curved cross section so that when a stud, such as shown at 18, is positioned thereon, the groove will serve as a cradle for holding the stud in a horizontal position with the ends of the stud arranged in alignment with the sides 19 of a link which is inserted between the concave surfaces of the die blocks 11 and 12 in a manner shown in Figures 1 and 2. The base 6 has two upwardly projecting flanges 20 and between these flanges is pivotally mounted the lower end portion 21 of an actuating lever 22; the pivotal connection consisting of a pin 23 which extends through the flanges 20 and through the lower end of the lever. The extreme lower end of the lever has a finger 24 adapted to engage between two lugs 25 and 26 on the plate 8 so that by rocking the lever 22, the plate 8 will be moved backward and forward between the portions 7, and the die block 11 and part 10 will also receive said movement of the plate 8.

The upper surface 27 of the lever 22 is preferably made convex in the direction of the length of the lever so that the lever when in the position shown in Figure 1 can be moved downward either by the engagement of a hammer, such as an automatic hammer, or a movable die member. Thus when the lever 22 is swung downward from the position shown in Figure 1 to the position shown in Figure 5, the die block 11 will be moved toward the die block 12 and considering that a heated link has been laid flat in position on the plate 8 between the die blocks and that a cold stud 18 has been positioned on the pedestal 15 such movement will cause the die block 11 to compress the sides of the link toward each other so that the sides of the link will be forced into locking engagement with the ends of the stud.

In order to provide space for other links which are connected to the link being operated upon, I preferably discontinue the portions 7 to provide channels 28; the plate 8 also having notches 29 serving as receptacles for the upright connecting links so that the latter will not interfere with the

compressive action of the sides of the link which is receiving its stud. I also preferably provide the base 6 with an extension 30 having a groove 31 providing a guiding channel for the other attached links so that it is an easy matter to manipulate the chain so as to move each of the links successively between the die blocks 11 and 12.

It will be noted that when the link is positioned between the die blocks that the pedestal will extend upward between the sides of the link so as not to be interfered with during the action of the device. If desired, the pedestal can be raised in any suitable manner such for example as by inserting spacers thereunder so that the studs can be held in proper position irrespective of the thickness of the sides of the links.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. Link stud inserting apparatus including a base; a movable and a fixed die block mounted on said base, and arranged for inserting a chain link therebetween; means slidably mounted on said base and having means for engaging said movable die block; curved means for supporting a stud inserted in said link; and a lever pivoted on said base and swingable to move said slidably means and with it the movable die block to force the sides of said link into locking engagement with the ends of said stud; substantially as described.

2. Link stud inserting apparatus including a base providing a guideway; a member movable on said guideway; die blocks positioned above said member and providing a space into which a link can be inserted with a stud between opposed portions of said link; and means for moving said member on its guideway, said member having a portion adapted to move one of said die blocks toward the other die block which is fixed with respect to said base in order to compress said portions of the link against the opposite portions of said stud; substantially as described.

3. Link stud inserting apparatus includ-

ing a base providing a guideway; a plate 60 slidable in said guideway; die blocks positioned above said plate and providing a space into which a link can be inserted with a stud between opposed portions of said link; and means for moving said plate in its guideway, said plate having a portion 65 adapted to move one of said die blocks toward the other to compress said portions of the link against the opposite portions of said stud; substantially as described.

4. Link stud inserting apparatus including 70 a base providing a guideway; a plate slidable in said guideway; die blocks positioned above said plate and providing a space into which a link can be inserted with a stud between opposed portions of said link; and a pivotally mounted lever, said plate having lugs spaced apart between which a portion of the lever engages whereby when the lever is swung the plate will be moved in its guideway; substantially as described.

5. Link stud inserting apparatus including a base; a stud supporting pedestal on 85 said base; a plate slidable on said base and having a hole through which said pedestal extends; die blocks positioned above said plate and spaced apart to allow a link to be inserted therebetween; and means for moving said plate whereby the die blocks will be relatively moved toward each other to 90 force the opposed portions of said link into contact with the stud while on the pedestal; substantially as described.

6. Link stud inserting apparatus including 95 a base; a stud supporting pedestal on said base; a plate slidable on said base and having a hole through which said pedestal extends; die blocks positioned above said plate and spaced apart to allow a link to be inserted therebetween, one of said die blocks being fixed with respect to said base and the other being movable with said plate; and means for moving said plate whereby the die blocks will be moved toward each other to 100 force the opposed portions of said link on to the end of said stud, said means including a swingable lever for engaging and operating said plate; substantially as described.

In testimony whereof I have signed my name to this specification in the presence of two subscribing witnesses.

JOSEPH JOHNSON.
